(57) **CLAIM**

The ornamental design for a law enforcement baton, as shown and described.

DESCRIPTION

The claimed law enforcement baton is used to replace or augment the standard issue baton, particularly where the standard baton cannot be used effectively or concealment is important.

FIG. 1 is a left side perspective view of the law enforcement baton showing my new design, with the right side being a mirror image thereof; and,

FIG. 2 is a front elevation view, with the rear elevation view being a mirror image.
